Patented July 5, 1921.

Inventor

F. M. Murray

By Watson E. Coleman
Attorney

UNITED STATES PATENT OFFICE.

FRANK M. MURRAY, OF CADYVILLE, NEW YORK.

WRENCH.

1,383,744.

Specification of Letters Patent. Patented July 5, 1921.

Application filed May 15, 1920. Serial No. 381,560.

To all whom it may concern:

Be it known that I, FRANK M. MURRAY, a citizen of the United States, residing at Cadyville, in the county of Clinton and State of New York, have invented certain new and useful Improvements in Wrenches, of which the following is a specification, reference being had to the accompanying drawings.

10 This invention relates to certain improvements in wrenches and is primarily an improvement on form of wrench embodied in my pending application, Serial No. 254,555 filed September 18, 1918, and allowed November 11, 1919.

15 It is an object of the present invention to provide a device of this general character embodying a slidable jaw and a slidable holding member coacting therewith together with novel and improved means whereby said jaw and member are connected.

20 Another object of the invention is to provide a novel and improved wrench wherein is embodied a slidable jaw and a slidable holding member coacting therewith together with means operating automatically to maintain the holding member substantially fixed in a desired adjustment along the shank.

25 30 The invention consists in the details of construction and in the combination and arrangement of the several parts of my improved wrench whereby certain important advantages are attained and the device rendered simpler, less expensive and otherwise more convenient and advantageous for use, as will be hereinafter more fully set forth.

35 The novel features of my invention will hereinafter be definitely claimed.

40 In order that my invention may be the better understood, I will now proceed to describe the same with reference to the accompanying drawings, wherein:

45 Figure 1 is a view in side elevation of a wrench constructed in accordance with an embodiment of my invention.

50 Fig. 2 is a fragmentary view, partly in section and partly in elevation, illustrating in detail certain features of my invention as herein embodied, and

55 Fig. 3 is a fragmentary view in elevation of the inner edge of the shank as herein disclosed.

55 As disclosed in the accompanying drawings S denotes an elongated shank of pre-

determined dimensions and which is provided at one end portion with a fixed jaw F. The free end portion of the shank S is reduced in width for a desired extent therealong, but the outer edge of the shank substantially throughout its entire length is straight and in continuity. The inner portion of the shank S, or that portion of maximum width, has its inner edge straight with the surface of said edge serrated or otherwise roughened as at 2 which will herein after be more particularly referred to.

60 Mounted upon the shank S is a movable or sliding jaw J capable of a slight rocking movement in a direction longitudinally of the shank S. Coacting with the jaw J is a locking or holding member M also slidably mounted on the shank S and also capable of a slightly rocking movement in a direction longitudinally of said shank. The locking or holding member M has one side portion extending beyond the inner edge of the shank S and said side portion has its opposite longitudinal margin defined by 65 the outstanding flanges 3 between the forward end portions of which is pivotally supported for locking movement a pawl or dog 4. The pivoted portion of the pawl or dog 4 is provided with an extension or tail 70 75 80 85 90 95 5 overlying the adjacent side of the member M and movable upon depression between the flanges 3. Interposed between the outer end portion of the extension or tail 5 and the adjacent side of the member M is a spring 6 which operates to constantly urge said extension or tail member 5 outwardly and cause the pawl or dog 4 to engage the inner edge of the shank S or more particularly the serrated or roughened portion of said edge, whereby the dog or pawl 4 automatically operates to maintain the locking or holding member M substantially fixed in the desired adjustment.

100 The serrated or otherwise roughened edge portion 2 provides means to prevent grease or other substances from affecting the bite of the jaw J upon the shank and also facilitates the requisite engagement of the pawl or dog 5 therewith. The outer end portion of the adjacent or coacting side of the member M is cut away as at 6^a between the flanges 3 to permit the requisite engagement of the dog or pawl 4 with the shank S.

105 110 The inner end of the side of the member M adjacent the inner edge of the shank S

is provided with an angular extension 7 which interlocks with an angular extension 8 carried by the adjacent or inner end portion of the jaw J so that the member M and the jaw J are caused to move in unison and in the same general direction along the shank S.

The outer side of the jaw J at its inner end is inclined or beveled as at 9 in a direction inwardly of said jaw and outwardly with respect to the shank S. The adjacent side of the member M is provided with an extension 10 having its inner face inclined or beveled and overlying the inclined or beveled edge or face 9 and which arrangement or assemblage is maintained by the interlocking or interfitting extensions 7 and 8 hereinbefore referred to.

When the jaw J has been properly adjusted relatively to the jaw F to engage the work, it will be understood that the resultant strain upon the jaw J during the working operation will slightly rock the jaw F and also the member M and thereby cause said member to frictionally bind against the shank S and thereby hold the jaw J in its desired position. It will also be self evident that the greater the strain imposed upon the jaw J the tighter the member M will grip the shank S.

The contact of the dog or pawl 4 with the inner edge of the shank S serves to hold the jaw J and the member M from slipping or moving longitudinally of the shank S and particularly between working operations. As is clearly disclosed in the accompanying drawings the tail or extension 5 of the dog or pawl 4 is disposed in the direction toward the jaw J so that said extension or tail 5 may be readily and conveniently depressed to free or release the dog or pawl 4 with respect to the shank S by pressure of the thumb or other digit of the hand grasping the shank S.

From the foregoing description it is thought to be obvious that a wrench constructed in accordance with my invention is particularly well adapted for use by reason for the convenience and facility with which

it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

1. A wrench comprising a shank, a slideable jaw movable thereon, a holding member slidably mounted directly on the shank and coacting with the slideable jaw, said jaw and member having inclined faces coacting one with the other when pressure is imposed upon the slideable jaw whereby the holding member holds said jaw against movement along the shank, and automatically operating means carried by the holding member for maintaining the same against movement along the shank between working operations and means connecting said holding member and slideable jaw whereby said member and slideable jaw move in unison upon the shank.

2. A wrench comprising a shank, a slideable jaw movable thereon, a holding member slidably mounted directly on the shank and coacting with the movable jaw, the opposite faces of the jaw and the holding member having coacting inclined portions, means connecting said jaw and member whereby said jaw and member shift simultaneously upon the shank, said jaw having rocking movement independently of the shank, the inner edge of the shank being roughened to facilitate the requisite biting of the jaw on the shank when strain is imposed upon the jaw and means normally locking the holding member in adjusted position.

In testimony whereof I hereunto affix my signature.

FRANK M. X MURRAY.
